UNITED STATES PATENT OFFICE.

JAMES W. MILLS AND ELMER E. IZER, OF POMONA, CALIFORNIA.

FOLDING FRUIT-SHIPPING RACK.

No. 804,492.

Specification of Letters Patent.

Patented Nov. 14, 1905.

Application filed July 1, 1905. Serial No. 267,976.

To all whom it may concern:

Be it known that we, JAMES W. MILLS and ELMER E. IZER, citizens of the United States, residing at Pomona, in the county of Los Angeles and State of California, have invented new and useful Improvements in Folding Fruit-Shipping Racks, of which the following is a specification.

Our invention relates more particularly to 10 folding racks for supporting fruit-baskets during shipment in railway-cars; and the object of our invention is to provide a rack of light and durable construction that can be folded up out of the way, so that the car can 15 be used for shipping other commodities when not used to ship fruit. It is also convenient in loading and unloading the baskets.

Another object is to provide efficient ventilation for the fruit during shipment.

20 Heretofore it has been usual in the shipment of citrus fruits in cars to pack the fruit in rectangular boxes and then to place the same one above the other in railway-cars. By this means it has been found that the placing 25 of the boxes so closely together in the cars has been extremely detrimental to the preservation of the fruit, as the close proximity of the boxes to each other prevents a free circulation of air around them, thus causing 30 premature decay. Recognizing the disadvantages of the above method of packing and shipment, it has lately become a custom to pack the fruit in cylindrical-shaped baskets with a cover and placing the same upon 35 wooden racks constructed for that purpose in the cars. This method has been found to be extremely inconvenient, as it necessitates a great deal of labor and expense in the construction of the racks and the trouble in re- 40 moving the same at the end of the journey for the removal of the fruit and so that the cars may be utilized for other shipments. To this end we have provided a folding rack that is both light and durable in construction and that 45 can be folded up when not in use, thereby leaving the car free to be utilized for other shipments.

In the accompanying drawings, Figure 1 is 50 a transverse section through a railway-car, showing our device in place therein. Fig. 2 is a horizontal section of a fragment of a box-car with our rack shown in plan therein. Fig. 3 is a perspective view of a fragment with a section of one of our racks in its ex- 55 tended position. Fig. 4 is a section of a fragment of our rack in its folded position. Fig.

5 is an enlarged perspective view of one of the rack-supporting sockets.

In the drawings we have shown the rack as constructed of angle and T irons properly braced together, forming a plurality of fruit-receiving sections A B C, each section being adapted to receive one or more baskets or crates 11 (shown in dotted lines in Fig. 1) of fruit. These sections are formed by the vertical supporting angle-irons 6 and T-irons 7, held together by horizontally-disposed angle-irons 8, pivotally secured to the upright supports 6 and 7, as at 9, and hinged together in the center, as at 10. The upright supports 6 are held in alinement by means of the steady- 65 ing-bar 12, adapted to hold the different sections in their proper places when the rack is loaded with fruit. These steadyng-bars are supported in place by the brackets 13, secured 70 to the angle-irons 6. Resting upon the angle-irons 8 and rigidly secured thereto are braces 16 and the fruit-supporting slats 17, adapted to support the baskets or crates of fruit when in place in the rack. In Fig. 1 we have shown 75 a transverse vertical section of a box-car, the section A being in position for the reception of the baskets or fruit-crates, the central section B being shown in a partly-collapsed position and section C being shown in a collapsed 80 position, in which position it will remain when the car is not in use for the transportation of fruit. These different parts are supported by the rack-supporting sockets 14, secured to the framework of the car and adapted to receive the downwardly-projecting lugs 15, rigidly secured to the uprights 6. In Fig. 4 we have shown a horizontal section of a fragmentary view of the racks in a collapsed position. 85

90 To equip a car with our improved rack, it will be necessary to place the sockets 14 in proper place on the frame of a car, these brackets being the only part of the rack necessary to be rigidly affixed to the frame of a car and the other portions thereof being easily removed. By this arrangement a rack can be put into its collapsed position out of the way, so that the car can be used for other purposes than the shipment of fruit, or the racks can 105 be removed altogether from the car, leaving only on the car the supporting-sockets.

110 The socket 14 (shown in Fig. 5) has an inwardly-inclined bearing-surface, the purpose of which is to take up any play which may exist in any of the connecting parts between the sockets on different sides of the car.

A car properly equipped with our fruit shipping racks always holds the fruit from being crushed and at the same time affords ample means to ventilate the fruit and at the same time provides means whereby the entire space in the car may be utilized for shipping fruit.

Having described our invention, what we claim as new, and desire to secure by Letters 10 Patent, is—

1. A rack for shipping fruit comprising a plurality of vertical standards; a plurality of horizontal supporting-bars pivotally connected thereto, the supporting-bars of one standard being pivotally connected to the supporting-bars of an opposing standard; and means to secure said rack in a car.

2. The collapsible rack for placement in a fruit-shipping car comprising in combination 20 the upright angle-irons 6 and 7, angle-irons 8 pivotally secured thereto and pivotally secured in the center; fruit-supporting slats rigidly secured to the angle-irons 8; and means to detachably secure the same to the box of a 25 car.

3. A rack for shipping fruit comprising a plurality of vertical standards; a plurality of horizontal supporting-bars pivotally connected thereto, said supporting-bars being centrally and pivotally united by upwardly-clos- 30

ing hinges; and means to secure said rack in a car.

4. The herein-described means to ship fruit in a car comprising upright supports 6 and 7 having pivotally secured thereto slat-supporting irons 8; slat-supporting irons 8 pivotally secured to the upright supports and having secured thereto the fruit-supporting slats 17 and braces 16 and the steadyng-bar 12 adapted to be supported by the brackets 13 riveted to the upright supports 6.

5. A rack for shipping fruit comprising a plurality of vertical standards; a plurality of horizontal supporting-bars pivotally connected to said standards, said supporting-bars being centrally and pivotally united by hinges which will prevent said bars from turning downwardly and will permit them to turn upwardly at their point of engagement; and means to secure said rack in a car; in combination with a car having rack-securing means affixed thereto.

In witness that we claim the foregoing we have hereunto subscribed our names this 22d day of June, 1905.

JAMES W. MILLS.
ELMER E. IZER.
